STEEL PERMANENT WAY FOR HIGH SPEED
RAILWAYSErnst Karl Roscher, Hamburg-Wandsbek,
GermanyApplication March 18, 1931, Serial No. 523,572
In Germany December 22, 1930

7 Claims. (Cl. 104—124)

The constructing of high speed railways normally proceeds on the assumption, with a view to reliable operation, that the permanent way is located in a zone which is entirely unhampered by ordinary traffic. Outside the towns this is mainly effected in the form of a raised embankment, which crosses country roads by means of bridges, whereas in towns an elevated railway structure made of steel is frequently employed.

On account of the high cost of such an elevated railway structure it has hitherto not been found advisable in practice to employ the same over long distances, notwithstanding the fact that it has the great advantage of only occupying a small amount of land for its foundations, and of easily bridging over differences in the level of the ground, and above all, of obviating any interference with the traffic on the land below it. Apart from the cost it is therefore technically the most advantageous type of permanent way.

The cost of an elevated railway structure passing through open country is directly dependent upon the heaviest train units which are to pass over the horizontally extending bridge girders between the supporting columns or abutments. These weights, in the case of trains drawn by locomotives of the heaviest type at present in use are very considerable.

If, however, the weights of the train units can be considerably reduced, and nevertheless a considerable amount of traffic can be adequately dealt with, the steel structure for elevated railways can compete on advantageous terms with the railway embankments hitherto adopted for long distance traffic, having regard to the difficulties associated therewith.

These light train units are possible now, more particularly in the form of light railway motors for passenger traffic, which are guided between lower carrying rails and supporting rails extending above the vehicles, and the weight of which is comparable with that of an aeroplane or of an automobile. A rail motor of this type for high speed railways forms the subject-matter of my co-pending application Ser. No. 523,571, filed March 18, 1931.

The construction of a railway structure especially for such vehicles and, particularly on a narrow gauge track, or preferably on a single rail, with a supplementary guiding rail above the vehicle, is contemplated by the present invention.

The arrangement of rails in high speed railway structures at present in use is such that the cars or trains either travel along above the bridge girder or travel through the interior of

a box-shaped bridge girder, or hang down therefrom as a suspended railway.

All three constructions are unsuited for a light and economical construction.

In the first case the bearer height is poorly utilized, and the centre of gravity of the moving load is located very high, if sufficient clear height is still to remain underneath the bridge. In the case of the usual box girder bridge and of a double track arrangement of rails, the bridge girder is comparatively broad and high, in order to allow room for the passage of the vehicles.

In the case of a suspended railway the weight of the bridge girder must be arranged high above the level, if the vehicle bodies hanging down underneath the bridge are to leave sufficient clear height for the traffic or the like located beneath them.

All the bridges, with the track arrangement as described, have the further disadvantage that, notwithstanding their great intrinsic weight, they only permit of a limited speed of the vehicles. The total weight of the supporting structure is furthermore so great that no-one has hitherto contemplated utilizing the rails for assisting in taking up the longitudinal stresses of the supporting bridge.

The present invention obviates the disadvantages of the constructions described, first owing to the fact that for each of the two tracks it provides a lower supporting rail and an upper guiding rail, which extend along beside the bridge girder on the two outer sides, in such a way, that the two lower rails are at about the height of the lower boom, and the upper rails are at about the height of the upper boom of the bridge girder.

The result is thereby obtained that the centre of gravity of the moving load is low, and also, for the bridge itself, that favourable conditions as regards freedom of the ground are attainable, that the bridge girder is narrow, and therefore relieved of unnecessary weight, that the lightest construction of the vehicle bodies is possible, and finally that the upper and lower rails may advantageously be utilized to assist in taking the longitudinal stresses of the bridge girder itself.

The drawings show by way of example various possibilities of construction and using such narrow and light bridge structures.

Fig. 1 shows in transverse section a bridge structure of triangular formation with monorails on the outside of the bridge body.

Figs. 2 and 3 show in transverse section a double T or double-cross formation of the bridge body

which in combination with the angular bracing between the vertical web members and the horizontal transverse members is practically speaking but a structural alternative of the structure 5 of Fig. 1.

Fig. 4 shows in cross section a modified bridge body with A-shaped struts the rails for the two tracks being arranged outside of the bridge body and also outside of the said A-frame, the cross 10 section of the cars is made narrow at the bottom and shaped so at one side that it fits closely to the triangular section of the bridge body.

Fig. 5 is a longitudinal elevational view of a bridge structure with a cross section according 15 to Fig. 1.

Fig. 6 is a longitudinal elevational view of a bridge body with cross sections similar to Fig. 2.

Fig. 7 is a longitudinal elevational view of a bridge body with cross sections according to 20 Fig. 3.

Fig. 8 is an elevational view of a continuous bridge body (i. e. without interruption of longitudinal booms between three abutments); the cross section in this case is advantageously similar 25 to Fig. 1.

Fig. 9 is an elevational view of a bridge body similar to Fig. 1 and Fig. 8 over large spans by suspending it on a suspension cable or cables between high piers placed at comparatively large 30 distance from each other.

Fig. 10 is a bottom plan of the base of the arrangement shown in Fig. 1 showing particularly the horizontal diagonal bracing.

A particularly advantageous utilization of material is obtained when adopting the fundamental ideas hereinbefore set forth if the vehicles are made particularly narrow at the lower part, and a girder construction is selected wherein the cross section exhibits the form of a triangle with the 35 apex at the top, as shown in Figure 1. As shown the transverse bearers 1 are connected by longitudinal booms or chords 1', the end portions of the bearers extending beyond the booms and supporting lower carrying tracks 2. The supporting 40 rails 3 arranged above the lower tracks are then kept the correct distance apart by means of transverse bearers 4 above the apex of the triangular frame, each transverse bearer being 45 strongly connected with the said frame.

This cross sectional form of bridge has the 50 advantage of great rigidity in all directions, particularly as regards torsional movements, since by the employment of rigid diagonals 14 as shown in the side view of the bridge in Figure 5, the 55 alterations in the angles at the corner connections of the girder are precluded. Further advantages are: that the lower rails 2 assist the lower longitudinal booms or chords which in taking up longitudinal stresses and can be located 60 close to the main struts 5, that is to say, the bridge girder web, and that the mounting of such a framework in the open country can be particularly simply and reliably carried out. If the idea of utilizing the upper supporting rails 65 3 as a longitudinal bond is substantially abandoned, the upper boom may extend in the form of a special profile 6 beyond the apices of the triangular frames, thus giving rise to the most advantageous possible position as regards web 70 construction.

In Figures 2 and 3, modifications of the basic form illustrated in Figure 1 are shown. The supporting structure is here in the form of a double T or in the form of a double cross, wherein stays 75 1, 8 and 9, or 10, 11 and 12 are employed in tri-

angular relationship in place of the rigid members 1, 4 and 5 in the cross sectional form shown in Figure 1. The corresponding side views of the bridge 8 are shown in Figures 6 and 7.

Figure 6 also shows that here the upper main boom is in the form of an arc 17, in which case it may be constructed with a constant cross section, thus utilizing the material as advantageously as possible.

It would of course also be possible to replace the 10 inclined stays 8 and 11 illustrated in Figures 2 and 3 by vertical stays joining the lower and upper cross girders outside the two vehicle bodies, the rails then being located nearer to the central vertical main bridge girder 13. The rigidity of 15 the construction then depends mainly upon the lateral strength of the central strut 13, and the horizontal diagonal bracing, which is arranged between the chords 1' and the lower transverse bearers 1 as shown at 21 in Fig. 10.

In cases in which an existing embankment is to be utilized, or in which guidance by an elevated track can be omitted, the cross girder constructions illustrated in Figures 1, 2 and 3 are also suitable for locating the lower and upper rail tracks upon such embankments, pile sub-structures and the like, because here again both the distance between the rails and the vertical position of the upper rail in relation to the lower rails must be secured as rigidly as possible.

The utilization of the rails for the longitudinal stresses in the body of the bridge is facilitated by fitting struts and stays 14, which are provided below and above them between the supporting points 15 and 16 of Figure 5 on the cross girders 35 of 1 and 4 of Figure 1, and which keep the bending stresses arising from the passage of vehicles small.

A particularly firm supporting pillar for the track bridge, which is at the same time easy to 40 erect, is shown in Figure 4 in the form of an A-girder, the shape of which grows, so to speak, out of the triangular cross section Fig. 1 of the bridge extending between such supports. As will be seen, in the case of these supporting pillars, 45 the vehicle bodies will pass laterally at the outside thereof, whereby they may be shortened to a minimum length, as contrasted with the triangular supporting pillars in suspended railways, where the vehicles pass through between the supporting pillars.

Of course some other form of support may also be employed in conjunction with girder bridges according to this invention.

In order to keep bending stresses small in the 55 bridge girders between the supports 18 in Figure 8, the bridge will preferably be constructed as a continuous girder over one or two supports.

In the case of rather long spans the type of bridge construction hereinbefore described may 60 advantageously be combined with a suspension cable 19, as shown in Figure 9, or a suspension chain, which is stretched between elevated supporting piers 20, and on which the bridge itself is suspended. Lateral oscillations of the bridge 65 are then precluded by special struts or holding cables. For this case also the rigidity of the triangle Fig. 1 is an important function.

It is to be noted that the upper longitudinal and transverse booms constitute an upper horizontal support and that the lower longitudinal and transverse booms constitute a lower horizontal support which supports are connected together by web members and form a continuous bridge body of open steel truss work. instances the carrying tracks also constitute an essential constituent of the upper and lower horizontal supports.

What I claim is:

- 5 1. A track structure for double track elevated railroad comprising a horizontal continuous bridge body of open steel truss work including at least one lower boom, at least one upper boom, transverse bearers connected therewith and extending laterally therefrom and truss bracing between the upper and lower booms and between the lower transverse bearers to make the lower and upper booms the bearers and the bracing act as one common girder, two upper stabilizing 10 tracks associated with the upper bearers, two lower carrying tracks on the outer ends of the lower transverse bearers, the lower carrying tracks being arranged on the outside of the bridge body in conjunction with the upper stabilizing 15 tracks above them and between which upper and lower tracks railway vehicles may run on and at the outside of the bridge body.
- 20 2. A track structure for a double track elevated railroad, as claimed in claim 1, wherein the longitudinally extending rail carrying tracks form additional longitudinal booms for the bridge body.
- 25 3. A track structure as claimed in claim 1, wherein the cross section of the bridge body is fundamentally in the form of a triangle with its

apex upwards and its base being extended laterally to carry the carrying rails of the vehicles.

4. A track structure as claimed in claim 1, wherein the cross section of the bridge body is fundamentally in the form of a triangle with its apex upwards and the longitudinal booms of the bridge girder being arranged at each corner thereof.

5 5. A track structure as claimed in claim 1, wherein the cross section of the carrying bridge 10 body is fundamentally in the form of an I.

6. A track structure as claimed in claim 1, wherein pillars are provided and constructed in the form of a roman capital A growing out of the triangular section of the bridge body while the 15 rails are carried along outside the profile of the said pillars.

7. A track structure for a double track high speed railway, comprising lower carrying rails and upper stabilizing rails between which the 20 vehicles can run, rail supporting structures between the two tracks shaped fundamentally in the form of a triangle with its apex turned up, horizontal rail bearers fastened to the apex of the said triangle and braced to the latter, the 25 tracks being mono-rail tracks for the use of vehicles the cross section of which is narrow in the lower portion and shaped to fit closely to the triangular rail supporting structure.

ERNST KARL ROSCHER. 30
